CLAIM

The ornamental design for a combined urine guard and toilet trainer with target, as shown and described.

DESCRIPTION

FIG. 1 is a rear, top exploded perspective view of a combined urine guard and toilet trainer with target showing my new design;

FIG. 2 is a front elevational view with the target attached;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.
